SEVERIN SIEBOLD, OF SYRACUSE, NEW YORK, ASSIGNOR TO HIMSELF
AND P. BURNS, OF SAME PLACE.

Letters Patent No. 101,386, dated March 29, 1870.

IMPROVED GAG-RUNNER AND BUCKLE.

The Schedule referred to in these Letters Patent and making part of the same

To all whom it may concern:

Be it known that I, SEVERIN SIEBOLD, of Syracuse, in the county of Onondaga and State of New York, have invented a new and useful Combined Gag-Runner and Buckle; and I do hereby declare the following to be a full, clear, and exact description of the nature, construction, and operation of the same, sufficient to enable others skilled in the art to which the invention appertains, to fully understand and use the same, reference being had to the accompanying drawings, which are made part of this specification, and in which—

Figure 1 is a side elevation of the device illustrating my invention.

Figure 2 is a front or edge view of the same.

Similar letters of reference indicate corresponding parts in the two figures.

My invention consists in combining a gag-runner and buckle by means of a hinged joint, so as to adapt the article to be more easily and cheaply manufactured, and render it capable of more satisfactory service than those commonly employed.

I cast the buckle A and gag-runner or swivel B by separate and distinct operations, and provide them with the counterparts of a hinge, respectively at the

lower cross-bar of the buckle and the top of the runner, which will admit of the free vibration or pivotal motion of the gag-runner. I thus attach the gag-runner to the lower end bar of the buckle A, leaving the center bar of the buckle free to hold the end of the throat-latch. The buckle attaches the gag-runner to and suspends it from the billet-strap of the headstall.

This mode of connection secures the untrammelled action of the swivel or gag-runner, as there is no strap or other object outside of or in a position to impede the outward motion of said gag-runner.

Having thus described my invention,

What I claim as new, and desire to secure by Letters Patent, is—

A gag-runner and buckle, united together by a hinged metallic joint at the lower cross-bar of the buckle and the top of the gag-runner, substantially as described.

The above signed by me this 23d day of February, 1870.

SEVERIN SIEBOLD.
